UNITED STATES PATENT OFFICE.

JOSEPH CONLEY, OF ANADARKO, OKLAHOMA.

LATRINE-INCINERATOR.

No. 926,099.

Specification of Letters Patent.

Patented June 29, 1909.

Application filed January 11, 1909. Serial No. 410,453.

To all whom it may concern:

Be it known that I, JOSEPH CONLEY, citizen of the United States, residing at Anadarko, in the county of Caddo and State of Oklahoma, have invented certain new and useful Improvements in Latrine-Incinerators, of which the following is a specification.

My invention relates to certain new and useful improvements in latrine incinerators and the object of my invention is to provide a device of this character which is simple in construction and at the same time has the highest efficiency.

With these objects in view my invention consists in certain constructions, combinations and arrangements of parts the preferred form of which will be first described in connection with the accompanying drawings and then the invention pointed out in the claims.

Referring to the drawings wherein I show the preferred form of my invention and wherein the same part is designated by the same reference numeral wherever it occurs: Figure 1 is a top plan view, the stack being shown in section; Fig. 2 is a vertical section taken on line 2—2 of Fig. 1; Fig. 3 is a vertical section of Fig. 2 taken on line 3—3 and looking in the direction of the arrows; Fig. 4 is a vertical section of Fig. 2 taken on line 4—4 and looking in the direction of the arrows; Fig. 5 is a horizontal section of Fig. 2 taken on line 5—5 and looking in the direction of the arrows, and Fig. 6 is a detail sectional view of one of the valves.

1 designates a rectangular furnace structure the bottom of which is adapted to support a fire; 2 are doors by which access is had to the interior of the furnace; 3 is the stack extending up from the furnace 1 and provided with a damper 4.

5 are four latrines arranged around the four sides of the furnace and connected thereto by means of the pipes 6 which form flues from the latrines to the central stack. These latrines are, as shown, similarly constructed, so that a description of one is a description of all.

7—7 are the side walls of the latrine; 8 is the front wall and 9 the back wall.

10 is a strip running centrally from the rear wall to the front wall and supported thereby at its ends.

11—11 are covers hinged, by means of the hinges 12, to the strip 10.

13 are openings in the covers 11 forming

seats, and these seats are closed by the covers 14 hinged at 15 to the covers 11.

16—18 are stops secured to the strip 10, one between each pair of covers 14, so as to support the covers in their raised position as shown in dotted lines in Fig. 3.

Two seats are shown in each of the covers 11, but it is to be understood that this number may be increased or diminished if desired.

Pivoted in the front and rear walls of the latrine are the pair of pans 17, each of the pans extending under the seats in one of the covers 11. These pans 17 are provided at each end with a projecting boss 18 on the outer end of which is formed the bearing collar 19, the boss also having the central depression 20.

21 is the journal which extends through a bearing opening in the walls and into the depression 20. The journal is squared at its outer end and is provided with a toothed collar 22 which bears against the outer surface of the wall, and 23 is a pawl pivoted on the wall and adapted to engage the teeth on the collar 22 to hold the pans in their several positions.

The journals are secured to the bosses by means of a bolt 24 which extends through the journal and into the boss, the inner end of the bolt being secured in the boss by the pin 25. The bolt on its outer end carries the nut 26 by means of which the parts are secured together.

It is to be understood that preferably only the outer collar 22 which bears against the end wall 8 is provided with the teeth, and that the journals for the pans at their other end is similar to that at the outer ends except that the collar has no teeth and that no holding pawl is provided.

In the lower portion of the front wall 8 is an opening provided with a door 27 by which access is obtained to the space beneath the pans 17. Preferably in this form of incinerator I do not provide a floor but leave the bottom open so that the lower edges rest upon the ground, and upon the ground beneath the pans I build the fires as indicated in Fig. 2, the draft for the fire being provided by digging channels under the front wall 8, as indicated at 28.

29 is a pipe which extends from near the upper edge of the outer wall 8 down nearly to the bottom of the wall where it enters the incinerating chamber through the wall in

front of the fire as indicated in Fig. 2. The purpose of this pipe is to carry the vapors and gases generated in the upper portion of the chamber down where they will come in 5 intimate contact with the fire as will be hereinafter described.

Mounted upon the upper portion of the rear wall 9 is a tank 30, the tank being secured to the wall by the bolts 31, as shown, 10 and the tank is further supported by the brackets 32. Each side of the tank is provided with a cover 33 hinged to a support 34 extending centrally across the top of the tank. Preferably, and as shown, I provide 15 means whereby these covers may be opened by the person desiring to use the same by pressing his foot on a convenient treadle, as shown, and this means consists of a lever 34 pivoted intermediate of its ends at 35 to the 20 side of the tank. The outer end of the lever is slotted at 36 and 37 is a pin carried by the cover 33 and entering the slot 36.

38 is an arm connected at one end to the inner end of the lever 34 by the pivot 39. 25 This arm passes through the slot 40 in the depending bracket 41 and at its lower end terminates in the foot pedal 42. The upper edge of the arm 38 is preferably formed with teeth 43 adapted to engage the upper 30 end of the slot 40 being yieldingly held in such engagement by the leaf spring 44 also carried by the bracket 41. From this construction it will be seen that when it is desired to raise a cover 33 its foot pedal 42 is 35 depressed and this raises the cover to the position shown in dotted lines in Fig. 4. By pressing the arm 38 inward the teeth 43 are disengaged when the cover can be readily lowered.

40 45 is a valve of any ordinary construction and has extending from it a pipe 46 which extends from the valve and through the wall of the tank and the adjacent rear wall 9 of the incinerator, the end of the pipe being 45 so located as to discharge into one of the pans 17, whereby when it is desired to evaporate the liquid in the tanks the valves may be opened to draw off the contents of the tanks and deliver them to the pans where 50 the liquid will be evaporated.

47 are troughs secured to the inner side of the side walls 7 above the pans 17, and beneath the front of the openings 13 these troughs are inclined toward the rear to carry 55 the liquid caught by them and deliver the same to the pans 48 located in the rear of the fire space on the bottom.

The pans 17, as best shown in Fig. 5, are 60 provided on one side with the projecting lugs 49, the lugs on one of the pans being adapted to engage the adjacent edge of the other pan. The lugs on the other pan are adapted to engage a projecting ledge 50 on the side wall 7. On the other side wall 7 I 65 provide the projecting lugs 51, with the

under side of which the adjacent edge of the pan engages. By this construction it will be seen that the pans are held in the position shown, but that they may be rotated in order to turn them over to dump 70 their contents onto the fire below.

In the operation of my construction a small fire is kept constantly in the central furnace, so as to constantly keep a draft in the stacks 3 and also to oxidize and deodorize 75 the gases and fumes which are given off by the matter in the latrines. When the pans 17 have become sufficiently filled with solid matter and the tanks 30 and the pans 48 filled with liquid, fires are built in the latrines. This evaporates the moisture in the solid matter contained in the pans 17 and also evaporates the liquid in the pans 48. The fumes and vapors given off pass through the pipes 29 and are delivered in front and 80 just over the fire, so that the fumes and vapors are completely oxidized and deodorized. The draft through the flues 6 is controlled by the dampers 52. When the solid matter in the pans 17 has been evaporated to 85 dryness a wrench is put on the squared ends 21 of the journals and the pans turned bottom side up dumping the solid matter remaining in the pans into the fire where it is completely consumed. The pans are then 90 turned back to their normal position and the liquid in the tanks 30 let into the pans by means of the valves 45. This liquid is 95 evaporated and after this has been completed the pans can again be turned over and their 100 inferior exposed to the direct action of the flames in order to thoroughly clean them. After the above described operations have been completed the fires in the latrines are allowed to burn out or they may be withdrawn; and as soon as the apparatus has cooled sufficiently it is again ready for use. 105

While I have described what I believe to be the preferred form of my invention, I desire to have it understood that many 110 changes may be made in the form, construction and arrangements of parts without departing from the spirit thereof.

What I claim as new and desire to secure by Letters Patent is:

1. In a latrine incinerator the combination 115 with a central stack having a combustion chamber formed in the lower portion thereof, of a series of latrines arranged around the stack, each comprising a casing, 120 pans mounted in the casing and separating the same into two portions, a pipe having its ends extending through the casing and connecting the upper and lower chambers, a flue extending from the lower chamber of 125 each latrine and connecting it with the stack, a tank supported over each flue outside of the casing, a valve pipe leading from each tank into the adjacent latrine and terminating over a pan, the lower compartment of 130

each casing below the pans forming a combustion chamber.

2. In a latrine incinerator the combination with a casing, of a series of seat openings in the top thereof, a pan mounted in the sides of the casing and dividing the same into two compartments, of an open trough supported on one of the sides of the casing beneath the front of the seats, inclined from end to end and extending under

a plurality of the seats with its lower end beyond the end of the pan, and a receptacle below the pan into which the trough drains.

In testimony whereof I affix my signature in presence of two witnesses.

JOSEPH CONLEY.
